UNITED STATES PATENT OFFICE.

JOHN H. DEAN, OF BIRMINGHAM, ALABAMA.

FASTENING MEANS FOR BUTT-JOINT METAL CULVERTS.

1,220,203.

Specification of Letters Patent. Patented Mar. 27, 1917.

Application filed January 23, 1913. Serial No. 743,766.

To all whom it may concern:

Be it known that I, JOHN H. DEAN, a citizen of the United States, residing at Birmingham, in the county of Jefferson and 5 State of Alabama, have invented certain new and useful Improvements in Fastening Means for Butt-Joint Metal Culverts, of which the following is a specification, reference being had therein to the accompanying drawing.

This invention relates to spring keys or clips for use in fastening together and maintaining in connected relation the complementary sections of my improved butt-joint 15 nestable metal culvert which I have particularly set forth and covered in Patent No. 1,049,816, granted to me on January 7, 1913.

The type of butt-joint nestable culvert herein referred to is one in which said culvert is made up of metal sections, preferably corrugated half sections, which sections have rigid metal strips or bars welded or riveted to the sides of said sections at or near their longitudinal edges, the strips or 25 bars being so arranged with respect to said metal sections that spaces or passageways are formed at intervals between the sections and said strips for receiving the spring keys or clips.

30 In assembling this type of culvert the complementary sections are placed together with their longitudinal edges meeting or abutting, and the spring key or clip to be hereinafter more particularly described, is 35 provided for engaging within the passageways formed between the sections and the strips with a view to providing a means for forcing the longitudinal edges of complementary sections into true abutting relation 40 and furthermore, for retaining said edges in such position. These spring keys are also adapted to serve as a means for connecting the adjacent strips of complementary sections together, whereby said complementary 45 sections are held and retained in proper assembled relation.

I have illustrated my invention in the accompanying drawings, in which,

Figure 1 is a side elevation of a butt-joint 50 culvert illustrating my improved spring key or clip in proper position for accomplishing the purpose for which it is intended;

Fig. 2 is a transverse sectional view taken on the line 2-2 of Fig. 1, and showing the 55 longitudinal edges of the culvert in abutting relation, and the spring keys inserted in

the passageways formed between the sides of the culvert sections and the metal strips;

Fig. 3 is a side elevation of one of the 60 spring keys; and

Fig. 4 is a perspective view of said spring 65 key.

Referring to the drawing, it is to be noted that each section indicated at 1 of the butt-joint culvert, is shown provided with corrugations which are arranged parallel with opposite ends thereof, and that when these sections which are preferably half sections are arranged in assembled position to form the completed culvert, the corrugations of 70 upper and lower sections coincide with each other, or in other words each convex and concave corrugation of an upper section is directly in line with the convex and concave corrugations respectively of the section below it. It is to be noted that these sections are constructed without the usual outstanding flanges, but that the longitudinal edges of complementary sections are adapted to abut as indicated at 2 in the drawing, so 75 that when said sections are connected together with their longitudinal edges meeting or abutting, the corrugated culvert, for all intents and purposes, has the appearance 80 and strength of an integral corrugated cylinder.

As has heretofore been referred to, the culvert sections are provided at or near their longitudinal edges with rigid metal strips or bars 3, which are secured to the convex 90 corrugations of each section, preferably by welding or riveting the same thereto, and it will be noted that passageways as indicated at 4, are formed between the sides of the corrugated culvert sections and the said 95 metal strips at points intermediate the convex corrugations of said sections, and these passageways are provided for receiving my improved spring key or clip.

The key or clip is made from a single piece 100 of spring metal and is substantially inverted U-shaped in form. This type of key is provided at its upper end with a flange indicated at 5, which is adapted to engage the upper strip or bar of complementary sections, in order to properly position said key within the passageway and prevent it falling entirely through the passageway when inserted. The key is also provided with a portion 6 which when said key is properly positioned within the passageway, engages the side of the culvert at a point where the longi- 110

ludinal edges of complementary sections abut and is furthermore provided with a portion 7 which is adapted to engage the inner face of both of the adjacent strips 3—3 of complementary sections. These portions or members 6 and 7, due to the fact that the key is made of spring metal, have a tendency to spread apart and when the key is inserted within a passageway, said members 6 and 7 will be forced into their desired engagement 10 with the side of the culvert and the metal strips 3—3, respectively, as will be readily understood. In such position of the key it is to be noted that the same serves to properly position and retain the longitudinal meeting edges of complementary sections in true abutting relation, and furthermore to connect adjacent strips of said sections for the purpose of holding the sections in assembled position. At the lower end of the member 7 of said spring key is provided an outwardly bent portion 8, which when the key is in proper position within the passageway, engages beneath the bottom edge of the lower strip 3 and thus serves to prevent accidental displacement of the key.

In providing a spring key or clip of the type just referred to, it will be noted that the key is capable of adjusting itself to passageways of different width, and this is due to the tendency of the members 6 and 7 to spread apart, in which event they are firmly held in engagement with the side of the culvert and the metal strips respectively.

Having thus described my invention, what I claim and desire to secure by Letters Patent is:—

1. In combination with a butt-joint culvert, a device formed with an outer face so shaped as to engage the side of said culvert at a point where the longitudinal edges of the same abut for holding and retaining said edges in such abutting relation, means for holding the device in such operative position, said device comprising a plurality of members at least one of which has a normal tendency to spring in an outward direction from the main structure, whereby the device is held in such position under spring tension.

2. In combination with a butt-joint culvert, a device formed with an outer face so shaped as to engage the side of said culvert at a point where the longitudinal edges of the same abut for holding and retaining said edges in such abutting relation, said device made up of a plurality of spring members, and means secured to the culvert for holding said device in such position and under spring tension.

3. In combination with a butt-joint culvert having passageways formed between the side of said culvert and metal strips secured to the same, a retaining means engaging within said passageways and comprising members held therein under spring ten-

sion, whereby said means is capable of adapting itself to passageways of different widths, one of said members being so constructed upon its outer face as to be capable of properly engaging the side of the culvert for holding and retaining the longitudinal meeting edges of said culvert in abutting relation.

4. In combination with a butt-joint culvert having passageways formed between the side of said culvert and metal strips secured to the same, a spring clip or key constructed from a single piece of metal bent upon itself to form retaining members, one of which members having an outer face so shaped as to bear against the side of the culvert when the key is inserted within said passageways for holding and retaining the longitudinal meeting edges of the culvert in abutting relation.

5. In combination with a butt-joint culvert having passageways formed between its side and metal strips secured to the same, a spring clip adapted for insertion within said passageways for holding and retaining the longitudinal edges of said culvert in abutting relation, said clip having a flange at its upper end adapted to engage the top edge of the upper strip and also having an outwardly bent portion for engaging with the bottom edge of the lower strip, and said clip adapted to be held within the passageways and in such relation under spring tension.

6. In combination with a butt-joint culvert having passageways between its side and metal strips secured thereto, a clip or key made of spring metal and of a form substantially U-shaped in cross section, said clip adapted for insertion within said passageways, in which position the clip is held under spring tension and serves to hold and retain the longitudinal meeting edges of the culvert in abutting relation.

7. In combination with a sheet metal culvert made up of complementary sections having longitudinal abutting edges and metal strips secured to the sides of said culvert sections along the longitudinal edges thereof for forming passageways between the culvert sides and said metal strips, a spring clip or key of inverted U-form engaging within said passageways, one member of said spring clip engaging the sides of said sections at a point where the longitudinal edges of the same abut, and the other member of said clip adapted to bear against the inner face of the metal strips.

8. In combination with a butt-joint culvert made up of complementary sections and having passageways formed between its sides and metal strips secured to said sides near the longitudinal edges thereof, a spring clip or key of U-form, one member of said spring clip adapted to engage the sides of

the culvert at the joint between the sections and the other member adapted to bear against the inner face of the metal strips, said clip having flanges at opposite ends 5 thereof for engaging the top and bottom edges of the upper and lower strips respectively of complementary sections, in which position the clip is held under spring tension and serves to hold and retain the longitudinal meeting edges of the culvert sections 10 in abutting relation.

9. In combination with a butt-joint culvert having passageways formed between the side of said culvert and the metal strips 15 secured to the same, a retaining means engaging within said passageways, said retain-

ing means having members which have a normal tendency to spread apart, whereby the retaining means is capable of adapting itself to passageways of different widths, 20 one of said members being so constructed upon its outer face as to be capable of exerting pressure against the side of the culvert for properly holding and retaining the longitudinal meeting edges of said culvert in 25 abutting relation.

In testimony whereof I have affixed my signature in presence of two witnesses.

JOHN H. DEAN.
